UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A CARD-MOUNT.

SPECIFICATION forming part of Design No. 31,953, dated December 5, 1899.

Application filed November 8, 1899. Serial No. 736,284. Term of patent 7 years.

To all whom it may concern:

Be it known that I, JOHN P. ODGERS, a citizen of the United States, residing in Philadelphia, Pennsylvania, have invented a certain 5 new and original Design for a Card-Mount, of which the following is a specification.

My design is fully shown in the accompanying drawing, the essential feature of the design being an oval border consisting of a 10 waved vine-like figure with projecting leaves and blossoms or berries, the border having at top and bottom a projecting figure composed of a series of scrolls and a central flower.

In the drawing the waved vine-like figure 15 of the border is represented at 1, the leaves at 2, the blossoms or berries at 3, the project-

ing end scrolls at 4, and the central flowers at 5.

Having thus described my invention, I claim and desire to secure by Letters Patent—

The design for a card-mount, substantially as herein described and as shown in the accompanying drawing.

In testimony whereof I have signed my name to this specification in the presence of 25 two subscribing witnesses.

JOHN P. ODGERS.
